PATENTED SEPT. 29, 1903.

E. M. AVERILL.

CRATE.

APPLICATION FILED AUG. 8, 1902.

NO MODEL.

UNITED STATES PATENT OFFICE.

ELIAS M. AVERILL, OF SPARTA, MICHIGAN.

CRATE.

SPECIFICATION forming part of Letters Patent No. 740,213, dated September 29, 1903.

Application filed August 8, 1902. Serial No. 118,952. (No model.)

To all whom it may concern:

Be it known that I, ELIAS M. AVERILL, a citizen of the United States, residing at Sparta, in the county of Kent and State of Michigan, have invented a new and useful Crate, of which the following is a specification.

This invention relates generally to shipping-crates, and particularly to a form of crate adapted for use in the transportation or storage of fruits, such as peaches, plums, apples, and the like.

The object of the invention is to provide a crate which shall combine simplicity and cheapness of construction with the highest efficiency and durability in use and one which may readily be collapsed or knocked down when desired.

A salient feature of the present invention is the manner in which the frame-pieces of the structure are associated to cause them mutually to brace each other and to counteract any tendency of crushing or yielding to superposed weight or lateral pressure.

With these and other objects in view, as will appear as the nature of the invention is better understood, the same consists in the novel construction and combination of parts of a crate, as will be hereinafter fully described and claimed.

In the accompanying drawings, forming a part of this specification, and in which like numerals of reference indicate corresponding parts, there is illustrated an embodiment of the invention capable of carrying the same into practical operation, it being understood that the elements therein exhibited may be varied or changed as to shape, proportion, and exact manner of assemblage without departing from the spirit thereof, and in the drawings—

Figure 1 is a view in perspective of a form of knockdown crate constructed in accordance with the present invention, showing the top closed. Fig. 2 is a similar view showing the top open. Fig. 3 is a sectional detail view, on an enlarged scale, showing the manner in which the frame-pieces are held assembled at the corners of the crate. Fig. 4 is a perspective detail view of a slightly-modified form of assembling device.

Referring to the drawings, there is illustrated a form of knockdown crate, comprising

ing a top and bottom frame 1 and 2 and four corner-posts 3. The corner-posts on two sides of the crate are connected by horizontally-disposed strips 4, forming a sheathing and which may be of any desired thickness and suitably spaced apart to provide for proper ventilation, said strips being in this instance exhibited as disposed on the outer sides of the posts, although it is to be understood that, if preferred, they may be secured to the inner sides and still be within the scope of the invention. The two ends of the crate are formed by vertical strips 5, secured each to two of the frame-pieces 6, forming a sheathing the grain of which extends in the same direction at both ends of the crate, these strips in this instance being shown as attached to the inner sides of the frame-pieces, although, if preferred, they may be secured to the outer sides thereof. The strips 5 are shown as being of such width that two of them will present an efficient closure at each end; but it is to be understood that, if preferred, they may be made of narrow strips, as shown on the sides, without departing from the spirit of the invention.

The top 7 and bottom 8 are formed of a strip or strips of wood secured to the frame-pieces 9, and in this instance to the inner sides thereof, although, if preferred, they may be secured to the outer sides, and which form a sheathing the grains of which extend at right angles to that of the sides.

Under the arrangement described it will be seen that the crate is composed of six separate and distinct sections, which when disassociated in a manner that will presently appear may be piled one on top of the other, thus to facilitate reshipment.

The manner of assembling the frame-pieces of the ends with the corner-posts consists in rabbeting the outer sides of the end portions of the frame-pieces at 10 and the inner faces 95 of the end portions of the corner-posts at 11, the depth of one rabbet being equal to one-half of the diameter of each of the parts. By this arrangement it will be seen that vertical or lateral strain will be removed from the sides and ends of the crate, as they will be taken up by the rabbets, thereby permitting the strips constituting the sides and ends to be made of very thin material, and thus at

once to lighten the structure and reduce its cost of production. The manner of assembling the top and bottom of the crate with the terminals of the frame-pieces of the corner-posts consists in providing the frame-pieces 9, which are secured to the top and bottom at each end and on the inner faces, with recesses 12, in which are housed fastening devices 13, which, as shown in Figs. 1 to 3, may be an ordinary nail, these fastening devices being passed through open-ended slots 14 in the corner-posts and similar slots 15 in the frame-pieces 9. It is intended that the walls of the recesses 12 and of the slots 14 and 15 shall be so closely juxtaposed that sufficient frictional resistance shall be presented to the fastening devices to prevent their disconnection in use, the provision of the recesses and of the slots operating to prevent cracking or splitting of the parts with which they coact. To effect a further rigid seating of the fastening devices within the parts with which they coact, it is designed that the nails 16, which hold the top 7 and bottom 8 in position, shall be closely disposed with relation to the said devices, as clearly shown in Fig. 3. Instead of employing a nail such as described for holding the sections of the crate assembled a piece of spring-wire 17 may be employed, as shown in Fig. 4, which may be stapled at 18 to the frame-pieces 6, the end of the wire being bent to project within the recess 12 and slots 14 and 15. When it is desired to raise the top 7, or, if the crate should be inverted, the bottom 8, which would then constitute the top, it will only be necessary to remove two of the fastening devices engaging the same frame-piece 9, those associated with the other frame-piece constituting a hinge to permit the top to be thrown back, as shown in Fig. 2. It will be observed by reference to Fig. 1 that the grain of the strips of the sides all extend in one direction, that of the ends at right angles thereto and that of the top and bottom at right angles to the ends, and by this arrangement the crate will be thoroughly braced and rendered rigid in use.

When the crate is to be knocked down for purposes of reshipment or the like, it will only be necessary to remove the eight fastening devices at the eight corners of the device to effect this result.

In the embodiment of the invention the features of the interlocked or rabbeted terminals of the frame-pieces and of the corner-posts are of the highest importance, as it is this arrangement that renders the structure rigid and thoroughly efficient in use.

Having thus fully described my invention,

what I claim as new, and desire to secure by Letters Patent, is—

1. A crate comprising upper and lower frame-pieces provided with terminal rabbets, corner-posts having terminal rabbets interlocking with those of the frame-pieces, a top and bottom having frame-pieces disposed between the upper and lower frame-pieces, and detachable fastening means passing through the rabbets of the corner-posts and upper and lower frame-pieces and into the top and bottom frame-pieces. 65

2. A crate comprising upper and lower frame-pieces provided with terminal rabbets having seats, corner-posts having terminal rabbets interlocking with those of the frame-pieces and provided with seats, a top and bottom having frame-pieces disposed between the upper and lower frame-pieces and provided with open-sided recesses, and detachable fastening means engaging the seats of the rabbets of the corner-posts and upper and lower frame-pieces and the recesses of the top and bottom frame-pieces. 75

3. A crate comprising upper and lower frame-pieces provided with terminal rabbets having open-ended slots, corner-posts having terminal rabbets interlocking with those of the frame-pieces and provided with open-ended slots, a top and a bottom having frame-pieces disposed between the upper and lower frame-pieces and provided with open-sided recesses, and detachable fastening means passing through the slots of the rabbets of the corner-posts and upper and lower frame-pieces 95 and into the recesses of the top and bottom frame-pieces. 85

4. A crate comprising upper and lower frame-pieces provided with terminal rabbets and connected by sheathing, the grain of which extends in the same direction at both ends of the crate, corner-posts having terminal rabbets interlocking with those of the frame-pieces and connected by sheathing, the grain of which extends at right angles to that of the ends, top and bottom frame-pieces disposed between the upper and lower frame-pieces and connected by sheathing, the grain of which extends at right angles to that of the sides, and fastening means passing through the rabbets of the corner-posts, upper and lower frame-pieces, and top and bottom frame-pieces. 100 105 110

In testimony that I claim the foregoing as my own I have hereto affixed my signature in the presence of two witnesses.

ELIAS M. AVERILL.
